UNITED STATES PATENT OFFICE.

FREDERICK BURGENER, OF OLNEY, ILLINOIS.

ADJUSTABLE FRAME FOR CLEANING CARPETS AND RUGS.

1,315,656.

Specification of Letters Patent.

Patented Sept. 9, 1919.

Application filed April 8, 1919. Serial No. 288,498.

To all whom it may concern:

Be it known that I, FREDERICK BURGENER, a citizen of the United States, residing at Olney, in the county of Richland and State 5 of Illinois, have invented a new and useful Adjustable Frame for Cleaning Carpets and Rugs, of which the following is a specification.

The object of my invention is to provide 10 a machine which is adjustable both as to height and as to length and which provides a convenient frame over which carpets or rugs may be stretched while being cleaned.

In the accompanying drawings illustrating 15 my invention Figure 1 is a perspective of the entire machine; Fig. 2 is a vertical section on line 2—2 of Fig. 1; and Fig. 3 is a horizontal section on line 3—3 of Fig. 2.

Like numerals designate like parts in the 20 several views.

Referring to Fig. 1 of the drawings, I provide base members 1 at the ends of which suitable hooks 2 are provided to fasten into the corners of the rug or carpet to be cleaned.

25 Attached to members 1 are uprights 3 to which are attached suitable spring clamps 5 having tongues 7 projecting through a slot 4 in each of the uprights 3 and adapted to engage any of the slots 8 in the telescopic 30 metal extensions 9. Extensions 9 are slidably mounted in suitable guides 10, preferably five for each upright. The upper ends of members 9 are provided with curved slots 11 to receive and hold the top horizontal bar 12. Member 5 is provided with a suitable handle 6 for moving it out of engagement with extension 9 when it is desired to raise or lower that member. Attached to uprights 3 by means of suitable

40 bolts or other fastening means 4 I provide telescoping horizontal bars or strips 13 having longitudinal grooves 14, extending through which is a suitable thumb-bolt or similar fastening member 16 by means of 45 which the bars 13 may be secured in any particular desired adjusted position. At the end, or near the end of each of the bars 13 I provide a strap 15 slidably engaging over the other bar whereby the two bars are held 50 in operative telescopic relation as will be understood by reference to Fig. 1.

The carpet or rug to be cleaned is fastened at the corners of the base members of the frame on the screw hooks 2, and stretched over the top horizontal bar 12. The frame 55 may be readily adjusted to the desired height by grasping the handles 6 of spring clamp 5 and pulling that member back so as to disengage its tongue 7 from the slot 8 into which it has projected, and raising the 60 metal extension 9 and the bar 12, and then allowing tongue 7 of spring clamp 5 to re-engage one of the slots 8 in member 9. The frame may be adjusted longitudinally by means of thumb bolt 16 and the telescopic 65 bars 13 which are slidable relative to each other.

It is within the contemplation of my invention to provide any suitable bracing and fastening devices and to make the different 70 parts of any suitable material, my preferred construction however being illustrated in the accompanying drawings.

What I claim is:

1. In an adjustable frame for cleaning 75 carpets and rugs, the combination of base members having hooks secured at opposite ends of each of said members adapted to engage the edge of the fabric to be cleaned, uprights attached to said base members, vertically adjustable extensions mounted on the uprights, a horizontal bar carried by said extensions and mounted loosely on the upper end of each, and means adjustably connecting the uprights to permit of longitudinal 80 adjustment of the frame.

2. In an adjustable frame for cleaning 85 carpets and rugs, spaced base frame members having carpet engaging elements at opposite ends of its base members, uprights 90 mounted on said base frame members, a top horizontal bar loosely supported on the upper ends of the upright extensions, upright extensions adjustably mounted on the uprights, said extensions having spaced slots, 95 a spring bolt of L-shape, mounted on the uprights and adapted to releasably engage in a slot in the adjacent extension, and telescopic means horizontally connecting the uprights in adjustable spaced relation, substantially as shown.

FREDERICK BURGENER.
